(57) **CLAIM**

The ornamental design for a flying disc toy, as shown and described.

DESCRIPTION

FIG. 1 is a perspective view of a flying disc toy.

FIG. 2 is a front elevation view thereof. The rear elevation view is identical with the front elevation view.

FIG. 3 is a top plan view thereof. The bottom plan view is identical with the top plan view.

FIG. 4 is a right side elevation view thereof. The left side elevation view is identical with the right side elevation view; and,

FIG. 5 is a cross-sectional view thereof taken along line 5—5 in FIG. 2.
